(57) **CLAIM**

The ornamental design for an automotive front fascia lip, as shown and described.

DESCRIPTION

FIG. 1 is a front perspective view of an automotive front fascia lip embodying our new design;

FIG. 2 is a top plan view thereof;

FIG. 3 is a bottom plan view thereof;

FIG. 4 is rear elevation view thereof;

FIG. 5 is a front elevation view thereof;

FIG. 6 is a right side elevation view thereof; and,

FIG. 7 is a left side elevation view thereof.

The broken lines in the drawings illustrate portions of the automotive front fascia lip that form no part of the claimed design.
